CHIMNEY CAP

Ezra W. Kepple, Greensburg, Pa.

Application February 18, 1939, Serial No. 257,123

12 Claims. (Cl. 72—88)

My invention is an improvement in ventilating chimney caps for terminal application to the outlet conduit of gases of combustion, as a flue or stack, to improve the draft thereof.

More particularly it is designed for use as a chimney cap for house flues made of brick or other refractory material, and is especially designed to assist and control the draft under all weather conditions. Generally stated the device 10 consists of a hollow coping or cap of concrete, terra cotta, sheet metal, or other suitable material having a supporting base and of particular external and internal shape best adapted to effect the desired results, as shall be more fully 15 hereinafter described.

Referring to the drawings showing the preferred constructions:

Fig. 1 is a perspective view of the cap, detached;

Fig. 2 is a central vertical section of a concrete cap, on the line II—II of Fig. 1, and of the upper end of a chimney flue;

Fig. 3 is a cross section on the line III—III, looking upwardly;

Fig. 4 is a view like Fig. 2, showing the cap as made of sheet metal;

Fig. 5 is a view like Fig. 1, showing a modified construction;

Fig. 6 is a cross section like Fig. 3 on the line 30 VI—VI of Fig. 5.

The device, when made of concrete or terra cotta, is adapted to be set upon the top course of a chimney 2 of brick or other material with an intervening mortar or cement binder 3.

It is generally square or rectangular in plan view, provided with a surrounding substantial base 4 which preferably overlaps the outer edges of the chimney, protecting it and the mortar from weather effect.

The main hollow interior of the cap is defined by inner wall surfaces 5 which coincide at the bottom with the inner faces of the chimney walls. Such faces 5 extend upwardly to near the top by four straight or slightly inwardly sloping planes, for convergence and gradual cross area reduction.

Near the top the interior cross area is abruptly restricted by the inwardly beveled shoulders 6 extending from the angular joint or bend 7 with faces 5 to the lower edges of the finally restricted square outlet opening 8, terminating at the extreme top of the cap.

Such opening is defined within the comparatively short inwardly inclined faces 9 beyond 55 which the four outer sides of the top of the

cap slope abruptly outwardly and downwardly in beveled face form, as at 10. The upper edges of such faces terminate as shown, forming the acute angle lips 11 which are efficiently useful in the entire functioning of the cap.

The four exterior wall faces of the cap terminate at the lower edges of the bevels 10, at which level 12 the faces are almost vertically straight and with but slight inward taper.

The walls increase in thickness downwardly 10 towards the base 4 and with an outer scotia curve of constant downwardly reduced radius as clearly indicated at 13, forming streamline surfaces on all four sides.

By such construction it will be seen that the 15 base 4 is of ample strength and weight, assisting in stability when in position, and with a pleasing architectural appearance. Incidentally, the bottom of the base may be provided with a surrounding V or other shape groove 14 for firm 20 anchoring engagement with the mortar or cement 2.

Assuming the usually difficult conditions of lateral winds, either directly against either of the four main exterior surfaces, or angularly 25 against any two of them, the lower concaved and upwardly tapering outer faces effect desired deflection of the currents, as indicated by the arrows Fig. 2.

As such currents move inwardly they are also 30 guided upwardly, while the final bevels 10, of say 30° to 45° to the horizontal, more or less, produce an abrupt upward and inward course. The combined effect of the wind currents is to thereby produce an uplifting suction draft on 35 the gases passing out through the cap.

Such gases likewise are caused to converge during their passage through the cap from bottom to top, and are finally further restricted abruptly by the inwardly beveled shoulders 6 40 and converging outlet 8, with resulting acceleration.

Ordinarily, in calm weather, the interior formation of the cap greatly contributes to and improves the natural draft of the chimney. 45 The effect of a breeze or wind in the manner described is to exert a slight assisting suction or partial vacuum, with a resulting improvement in accelerating and stabilizing the draft of the main chimney or flue. Such advantageous results 50 have in fact been secured by prolonged actual use of my construction under the various conditions mentioned.

While satisfactory results are secured by the concrete construction as above described, the 55

cap may also be very efficiently made of sheet metal, as in Fig. 4.

The general proportions may be maintained as to both external and internal faces, but utilizing a downward extension of the inner face wall members for insertion into the top of the chimney, and with a very slight variation from upward tapering to substantially vertical formation of these members.

10 In such construction I utilize a rectangular base plate 4a for placement on the chimney top, to which the inner box-like shell 5a and the outer shell 13a are connected, as by welding or other suitable means.

15 Inner shell extends through and sufficiently below base plate 4a for close interfitting engagement within the top portion of chimney 4, so that either with or without the mortar 3 the entire cap will be firmly mounted in position.

20 At its upper end shell 5a is bent inwardly to form the beveled draft constricting shoulders 6a beyond the angular bends 7a and terminates in the finally restricted square outlet opening 8a, within the surrounding upper edge terminals 25 9a of the inner shell.

The upper terminal portions of outer shell 13a are bent inwardly over the terminals of the inner shell at confining angles and are secured thereto, as by welding, providing the final bevel faces 10a terminating inwardly in the angle lips 11a.

25 Outer sections 13a extend downwardly from the lower edge 12a of bevel 10a substantially straight for a limited distance and then gradually concavely outwardly, terminating in the outer edges of the base portion, as in Figs. 1 and 2.

Such lower edges of the outer walls are securely connected with the base plate 4a, as by welding.

It will be understood of course that in sheet metal construction the inner and outer sections together provide and constitute in effect the main surrounding wall portions of the complete cap, although with intervening hollow spaces, instead of being continuously solid.

Otherwise than by the substitution of sheet metal for concrete, the general construction closely conforms in all essential respects as to proportions, inner and outer surfaces, etc. and functions and gives results in operation as described, and with equal facility in manufacture and use.

50 I show in Figs. 5 and 6 a further modification of the molded or concrete embodiment of the invention, generally similar to that of Figs. 1, 2 and 3, but with additional useful features facilitating confining and deflecting control of wind currents.

In such the main elements and features are retained comprising the laterally extending base 4b for placement on the chimney 2b, with the inner faces 5c leading up to the inwardly beveled shoulders 6b for construction of the gases of combustion in their passage towards and out of the top opening 8b within the surrounding edge faces 9b. The outer wall faces are concavely formed as at 13b leading upwardly to the edges 12b at the bases of bevel faces 10b leading inwardly to the edges 11b of the middle outlet opening.

70 For the purpose of providing supplemental wind control and restriction each of the several corner edges of concaved surfaces 13b are provided with comparatively narrow outwardly extending webs or fin-like flanges 15b extending from top to bottom of the cap. These act as obstructing wind dams tending to more or less

centralizing confinement of the currents, with resulting increase in their effect in passing upwardly over one, or both concave faces of adjacent walls, as already described.

They are further useful in stiffening and bracing the cap at each corner, and add to the architectural appearance of the device.

While the general proportions of either form of the device should be approximately as illustrated, it will be understood that they, or matters of size, dimensions, material, or other incidental matters may be changed or varied from without departure from the principle of the invention and within the scope of the appended claims.

What I claim is:

1. A rectangular chimney cap as described having a supporting base of maximum size for placement on a chimney and extended upwardly forming a wall around a middle gas circulation opening with inner confining faces terminating in a constricted shouldered outlet opening, the outer faces of the cap converging inwardly from the rim of the base and concaved upwardly with increasing radii to a common transversely plane, and then angularly deflected inwardly and upwardly to the edges of the outlet opening to form beveled air deflecting faces adjacent the outlet opening.

2. A rectangular chimney cap having four transversely straight walls enclosing a middle gas outlet opening defined within upwardly and inwardly disposed inner wall faces terminating in a restricted upwardly tapering discharge opening, the outer wall faces flaring concavely outwardly in formation of a laterally extending base and thereabove in substantially plane upper inwardly tapering formation and having terminal inwardly and upwardly sloping bevel faces extending inwardly to the edges of the discharge opening.

3. A rectangular molded chimney cap having four integral transversely straight walls enclosing a middle gas outlet opening defined within upwardly and inwardly disposed inner wall faces terminating in a restricted upwardly tapering discharge opening, the outer wall faces flaring concavely outwardly in formation of a laterally extending base and thereabove in substantially plane upper inwardly tapering formation and having terminal inwardly and upwardly sloping bevel faces extending inwardly to the edges of the discharge opening.

4. A rectangular molded chimney cap having four integral transversely straight walls enclosing a middle gas outlet opening defined within upwardly and inwardly disposed inner wall faces terminating in a restricted upwardly tapering discharge opening, the outer wall faces flaring concavely outwardly in formation of a laterally extending base having a mortar engaging recess, the upper portions of the wall faces being in substantially plane slight inwardly tapering formation and having terminal wind deflecting bevel faces extending inwardly to the edges of the discharge opening whereby to effect an uplifting suction draft on converging gases issuing through the tapering discharge opening at the top of the cap.

5. An integral chimney cap of concrete consisting of surrounding walls having a relatively wide supporting base, the inner faces of said walls extending upwardly towards the top, then disposed more abruptly inwardly and then upwardly with slight inward taper forming a restricted

discharge opening, the outer wall faces being concaved from the outer edges of the base and thereabove with increasing radii and terminating in upper inwardly disposed plane surfaces, 5 and having final wind deflecting bevel faces extending inwardly to the edges of the discharge opening.

6. A chimney cap of sheet metal consisting of an inner gas circulation section terminating in an upper constricted shouldered outlet opening, a 10 surrounding base plate of maximum size for placement on a chimney, and an outer wind deflecting section connected with the base plate having lower faces converging inwardly and concaved upwardly and bent inwardly over and secured to the top portion of the inner section to 15 form beveled air deflecting faces adjacent the outlet opening.

7. A chimney cap of sheet metal consisting of an inner gas circulation section terminating in an upper constricted shouldered outlet opening, a surrounding base plate of maximum size for placement on a chimney, and an outer wind deflecting section connected with the base plate 25 having lower faces converging inwardly and concaved upwardly and bent inwardly over and secured to the top portion of the inner section terminating at the edges of the outlet opening and forming beveled air deflecting faces adjacent the 30 outlet opening.

8. A chimney cap as in claim 6 wherein the inner section extends downwardly below the base plate for engagement within a chimney top.

9. A chimney cap as in claim 3 wherein the 35 several corners between adjacent concaved outer faces are provided with outwardly extending wind arresting extensions.

10. A chimney cap as in claim 3 wherein the several corners between adjacent concaved outer faces are provided with outwardly extending integral wind arresting extensions in the form of comparatively thin flanges. 5

11. A rectangular chimney cap as described having a supporting base of maximum size for placement on a chimney and extended upwardly forming a wall around a middle gas circulation opening with inner confining faces terminating below inwardly disposed upwardly sloping restricting shoulders having inwardly disposed faces terminating in a constricted outlet opening, the outer faces of the cap converging inwardly and upwardly from the rim of the base to a common transverse plane, and then angularly deflected inwardly and upwardly to the edges of the outlet opening to form beveled air deflecting faces adjacent the outlet opening. 10 15

12. A rectangular chimney cap as described 20 having a supporting base of maximum size for placement on a chimney and extended upwardly forming a wall around a middle gas circulation opening with inner confining faces terminating below inwardly disposed upwardly sloping restricting shoulders having inwardly disposed faces terminating in a constricted outlet opening, the outer faces of the cap converging inwardly and upwardly above the base in substantially 25 plane inwardly tapering formation and having terminal inwardly and upwardly sloping bevel faces extending inwardly to the edges of the outlet opening. 30
